TUNING DEVICE FOR MUSICAL INSTRUMENTS

Filed May 17, 1930

Allen Loomis

By Louis C. Vanderlip.

Attorney

UNITED STATES PATENT OFFICE

ALLEN LOOMIS, OF ELKHART, INDIANA, ASSIGNOR TO C. G. CONN, LTD., OF ELKHART, INDIANA, A CORPORATION OF INDIANA

TUNING DEVICE FOR MUSICAL INSTRUMENTS

Application filed May 17, 1930. Serial No. 453,344.

This invention relates to wind musical instruments of the reed type.

The principal object of the invention is to provide an improved tuning device for wind musical instruments of the clarinet type, or any similar reed musical instrument.

Another object of my invention is to provide a joint between the instrument mouthpiece and the instrument body in which a tuning device is incorporated.

A third object of the invention is to provide an improved tuning barrel joint for clarinets, and the like, wherein one end telescopes into the tubular instrument body and the other end is provided with a socket for receiving the end of the clarinet mouthpiece.

Other objects of my invention are mentioned and described herein.

The preferred embodiment of my invention is illustrated in the accompanying drawings, wherein

Figure 1 is an exterior view in elevation showing the assembled tuning barrel joint;

Fig. 2 is a similar view in section;

Fig. 3 illustrates an exterior elevational view of an assembly composed of several only of the parts of the tuning barrel joint;

Fig. 4 is an exterior elevational view of the outside sliding sleeve;

Fig. 5 is a perspective of the same member;

Fig. 6 is a sectional elevational view of the adjusting nut;

Fig. 7 is a plan view of the thrust or locking ring; and

Fig. 8 is a section taken on line 8—8 of Fig. 2.

Similar numerals of reference indicate like parts throughout the several views on the drawings.

Referring now to the drawings and particularly to Figures 1 and 2, wherein an assembly of my improved tuning device is illustrated, the device comprises, generally, the mouthpiece receiver or holder 1; the guide member 2 rigidly connected therewith; the inside tubular slide element 3 rigidly connected in the bore of member 2; the outside sliding sleeve 4; the adjusting nut 5 which sleeves elements 2 and 4 and which is screw threaded to member 4 for longitudinally ac-

tuating the latter, and the mouthpiece—not shown—to be carried thereby; and the thrust or locking ring 6 which retains said adjusting nut in operative relation with members 1 and 2.

The sliding sleeve 4 may be provided with a cork sleeve 7 which is adapted to fit and seal within the tubular end of a clarinet, or like instrument. The guide element 2 may be ring-like in formation and is provided with the integral annular channeled head section 8 which has its depending annular flange section 9 rigidly connected with the bore of the cylindrical member 1 by a screw thread connection at 10 to which may be added solder to effect a permanent connection thereat.

The annular channel in head 8 of element 2 is somewhat loosely engaged by the annular outwardly extending flange 11 formed on the outer end of the tubular adjusting nut 5, the arrangement of said nut flange in said head channel being rotatably maintained by the thrust or locking ring 6 which may be removably screw threaded into the lower portion of the screw threads 10.

When ring 6 is thus mounted in the end of the member 1 and into contact with the lower end of the head flange 9 and into overlapping relation with the nut flange 11 it enables free rotative movement of the nut 5 and its flange 11 in said channel, and whereby displacement of the nut flange 11 is prevented. The ring 6 may be provided with a plurality of wrench sockets 12 to enable wrench application thereto for operation of said ring into and out of engagement with the screw threads 10.

The guide member 2 is provided with a pair of opposed prongs 13 and 14 which project longitudinally of the slide 3 into the interstices of a similar pair of prongs 15 and 16 formed on the end of the tubular slide member 4 which sleeves element 3. The tubular adjusting nut 5 encompasses the upper end of element 4 and the prongs 13 and 14 of guide member 2, there being a screw thread connection at 17 between the bore of said nut and the exterior of member 4 adjacent the base of the prongs 15 and 16. The slide 3 is preferably soldered into the bore of member 2.

As heretofore stated the cork sleeve 7 on the

end of member 4 is adapted to be thrust into the open bore of a clarinet body, or like instrument, and when thus arranged, the tone of the instrument may be altered by rotating 5 the nut 5 which causes the nut to advance longitudinally of the sleeve 4, thereby effecting longitudinal sliding movement of the members 1, 2 and 3, whereby the air column within the member 3 may be changed at will, ac- 10 cording to the direction of rotation of the nut 5.

I claim:

1. A combined tuning device and joint of the character described comprising a tubular mouthpiece holder, a ringlike guide member provided with an annular enlarged channeled head which is rigidly mounted in the bore of said holder, a tubular slide member rigidly connected with said guide member, a tubular 15 member slidably sleeving said tubular slide member, a non-advancing adjusting nut rotatably connected with the channeled head of said guide member, a complementary spiral connection between said adjusting nut and the 20 slide sleeve, and means connecting said guide member and slide sleeve to cause the latter to move reciprocally when said adjusting nut is rotated.

2. A combined tuning device and joint of the character described comprising in combination a tubular mouthpiece holder, a ring-like guide member provided with an annular enlarged channeled head which is rigidly mounted adjacent one end of said holder, a tubular slide member rigidly connected with said guide member, a tubular member slidably sleeving said tubular slide member, a non-advancing tubular adjusting nut rotatably connected with the channeled head of 35 said guide member, a complementary spiral connection between said adjusting nut and the tubular slide member, and a complementary prong and slot connection between said guide member and the tubular slide member to cause the latter to move reciprocally when said adjusting nut is rotated.

3. A combined tuning device and joint of the character described comprising in combination a tubular mouthpiece holder, a ring-like guide member provided with an enlarged head which is rigidly mounted upon said holder adjacent one end thereof, a tubular slide member rigidly mounted in said guide member axially thereof, a tubular member 50 slidably encompassing said slide member, a tubular rotatable adjusting nut, a complementary flange and groove connection between said adjusting nut and the guide member head, a complementary spiral connection 55 between said adjusting nut and the tubular slide member, and a complementary prong and slot connection between said guide member and the tubular slide member to cause the latter to move reciprocally when said adjusting nut is rotated.

4. A combined tuning device and joint of the character described comprising in combination a tubular mouthpiece holder, a ring-like guide member of lesser diameter than said holder and provided with an enlarged 70 head which is rigidly mounted upon said holder adjacent one end thereof, a tubular slide member rigidly mounted in said guide member axially thereof, a tubular member 75 slidably encompassing said slide member, a tubular rotatable adjusting nut, a complementary flange and groove connection between said adjusting nut and the guide member head, a complementary spiral connection between said adjusting nut and the tubular slide member, and means connecting said guide member and slide member to cause the latter to move reciprocally when said adjusting nut is rotated.

5. A combined tuning device and joint of the character described comprising in combination a tubular mouthpiece holder, a ring-like guide member provided with an enlarged head which is rigidly connected with said holder adjacent one end thereof, a tubular slide member rigidly mounted in said guide member, a tubular member 80 slidably encompassing said slide member, a tubular rotatable adjusting nut, a complementary flange and groove connection between said adjusting nut and the guide member head, one wall of said groove being removable to enable removal of said adjusting nut, a complementary spiral connection between said adjusting nut and the tubular slide member, and a complementary prong and slot connection between said guide member and the tubular slide member to cause the latter to move reciprocally when said adjusting nut is rotated.

6. A combined tuning device and joint of the character described comprising a tubular mouthpiece holder, a ring-like guide member provided with an enlarged head which is rigidly mounted upon said holder adjacent one end thereof, a tubular slide member rigidly mounted in the bore of said guide member, a tubular member slidably encompassing said slide member and slidably connected with said guide member, a tubular rotatable adjusting nut, a complementary spiral connection between said adjusting nut and the tubular slide member, and a complementary flange and groove connection between said adjusting nut and the mouthpiece holder to prevent longitudinal movement of said adjusting nut when the latter is rotated, said connection lying wholly within said mouthpiece holder.

7. A combined tuning device and joint of the character described comprising a tubular mouthpiece holder, a ring-like guide member provided with an enlarged head which is rigidly mounted in the bore of said holder, a tubular slide member rigidly 120

- mounted in the bore of said guide member, a tubular member slidably encompassing said slide member and slidably connected with said guide member, a tubular rotatable 5 adjusting nut, a complementary spiral connection between said adjusting nut and the tubular slidable member, and a complementary flange and groove connection between said adjusting nut and mouthpiece holder 10 to prevent longitudinal movement of said adjusting nut when the latter is rotated, said connection including a ring-like thrust member which is rigidly mounted in the bore of said mouthpiece holder.
- 15 8. A combined tuning device and joint of the character described comprising a tubular mouthpiece holder, a ring-like guide member provided with an enlarged head which is rigidly mounted in said holder, a 20 tubular slide member rigidly mounted in said guide member, a tubular member slidably encompassing said slide member and slidably connected with said guide member, a tubular rotatable adjusting nut, a complementary spiral connection between said adjusting nut and the tubular slidable member, and a complementary flange and groove connection between said adjusting nut and mouthpiece holder to prevent longitudinal 25 movement of said adjusting nut when the latter is rotated, said connection including a ring-like thrust member which is removably mounted in the bore of said holder.
